RALPH H. WEST, OF VANDERGRIFT, PENNSYLVANIA.

MOLD FOR CASTING CHILLED ROLLS.

No. 830,692.

Specification of Letters Patent.

Patented Sept. 11, 1906.

Application filed March 23, 1906. Serial No. 307,689.

To all whom it may concern:

Be it known that I, RALPH H. WEST, a citizen of the United States of America, residing at Vandergrift, in the county of Westmoreland and State of Pennsylvania, have invented certain new and useful Improvements in Molds for Casting Chilled Rolls; and I hereby declare the following to be a full, clear, and exact description of the invention, so such as will enable others skilled in the art to which it pertains to make and use the same.

This invention relates to improvements in molds for casting chilled rolls.

The primary object of this invention is to provide a roll-casting mold for the successful manufacture of chilled rolls in obtaining castings in daily practice which are acceptable and suitable for the production of a roll-forming casting in which the chilled peripheral crust or shell of the roll-body is uniform in thickness circumferentially of the casting, free from checks or cracks, as well as free from gas-holes and other imperfections, and found to be perfectly round when put in a lathe to be turned.

With this object in view and to the end of realizing other advantages hereinafter appearing this invention consists in certain features of construction and combinations of parts hereinafter described, and pointed out in the claims.

In the accompanying drawings, Figure 1 is a central vertical section of a roll-casting mold embodying my invention. Figs. 2 and 3 are horizontal sections taken through the upper mold part or cope on lines 2 2 and 3 3, respectively, Fig. 1. Only the upper part or cope is illustrated in Figs. 2 and 3 and Fig. 2 is drawn on a considerably larger scale than Figs. 1 and 3. Figs. 4 and 5 are horizontal sections taken through the lower mold part or drag on lines 4 4 and 5 5, respectively, Fig. 1, but in Fig. 4 the loam or sand of the drag is omitted. Fig. 6 is a sectional view illustrating a portion of the central mold part or chill. Fig. 7 is a central vertical section of the casting-depressing pressure-exerting ring *m* and illustrates the said ring on a larger scale than shown in Figs. 1 and 3. Fig. 8 is a vertical section in detail on either line 8 8, Fig. 4, and drawn on a larger scale than Figs. 1, 4, and 5.

My improved roll-casting mold comprises a lower mold part or drag *A*, a central mold part or chill *B*, and an upper mold part or cope *C*.

The drag *A* is cylindrical and provided

with a cavity 10, arranged centrally of the drag and extending from the upper extremity of the drag downwardly a suitable distance.

The chill *B* is cylindrical and provided internally with a cylindrical chamber 12, which extends vertically through the chill.

The cope *C* is cylindrical and provided centrally with a chamber 13, extending vertically through the cope.

The body of the roll to be cast is formed in the chill *B*, whereas the trunnions or necks of the roll are cast in the drag and cope. The drag-cavity 10 and the cope-chamber 13 are arranged centrally of and diametrically smaller than but in communication with opposite ends respectively of the chill-chamber 12 and have the general outline required to form the trunnions or necks of the roll to be cast. The surrounding wall or walls 15 of the cavity 10 and the bottom of the said cavity are built up of loam or molding-sand within a metal casing *D*, which surrounds the body of loam or sand forming the said bottom and walls. The cavity 10 is provided at one side and a suitable distance below the upper end of the cavity (see Fig. 1) with an inlet 16 for molten metal, and the mold is poured through the said inlet.

The chill *B* is mounted upon the upper end of the casing *D*, and the surrounding wall of the chill-chamber 12 is corrugated annularly or circumferentially from end to end or approximately from end to end of the chill, (see Figs. 1 and 6,) and the annular grooves *b* and annular beads 17, which are formed internally of the chill, alternate and avoid the formation internally of the chill of a substantially smooth and continuous or unbroken surface extending any material distance longitudinally of the chill. The surrounding wall of the cope-chamber 13 is formed by a body of loam or molding-sand which is built up within and surrounded by a metal casing *E*, mounted upon the chill *B*.

The chill-grooves *b* form vertically-spaced diametrical or lateral enlargements of the chill-chamber 12. The top and bottom walls of each groove *b* slope downwardly and inwardly; but the slope of the bottom wall of the lower of two adjacent grooves *b*, which slope is regarded as more especially important, is preferably less than the slope of the bottom wall of the upper of the said grooves, as indicated more clearly by the illustrative dotted lines *d* in Fig. 6. It will be observed,

therefore, that my improved roll-casting mold comprises a vertically-arranged chill, which is provided interiorly with a chamber which extends from the upper end to the lower end of the chill, with the surrounding wall of the chamber provided with a row of annular or circumferentially-extending grooves or lateral chamber enlargements, with the said row extending from end to end 5 of the chill, with the grooves or chamber enlargements of the said row spaced vertically at comparatively short intervals. It will be observed also that each bead which is formed between two adjacent grooves or chamber enlargements *b* is undercut at the bottom to form the downwardly and inwardly sloping top wall of the lower of the said grooves or chamber enlargements, that the top or upper surface of the said bead is 10 beveled to form the downwardly and inwardly sloping bottom wall of the upper of said grooves or chamber enlargements, and that the slope of the bottom wall of the upper of the said adjacent grooves or chamber 15 enlargements is greater than the slope of the bottom wall of the lower of the said grooves or chamber enlargements, so that the slopes of the bottom walls of the enlargements *b* of the chill-chamber 12 gradually increase toward the upper end of the chill. 20

17, formed between two adjacent grooves *b*, is rounded, as at 18, (see Fig. 6,) at the junction of the face of the said bead with the top wall of the lower of the said grooves. I would here remark, however, that the depth of the grooves *b* is exaggeratedly illustrated. 25

In casting a roll by my improved mold the 30 peripheral crust or shell of the casting formed in the chill is during its contraction maintained in a strictly central position relative to the chill and supported circumferentially of and upon the downwardly-sloping bottom walls of the grooves or chamber enlargements *b*. The casting is consequently supported until near its final contraction at as many intervals vertically as there are grooves or chamber enlargements *b*, so that 35 the said shell or crust is not liable to be checked or cracked or out of round or rendered defective by the pressure of molten metal within and centrally of the casting being formed. 40

It is obvious that the grooves *b* should have such depth that when the casting formed in the chill has cooled sufficiently the external annular ribs or beads formed on the casting in the said grooves shall be free from 45 the said grooves, so as to permit the hoisting of the chill from the casting. 50

A feature of considerable importance is the downward slope of the bottom walls of the grooves *b* and the increase in the slope 55 of the bottom walls of the grooves toward

the upper end of the chill, so as to hold the contracting casting centrally of the chill and evenly supported along its whole length from the said walls until the casting has contracted enough to become released from the 70 grooves, thereby producing a roll-body which is perfectly round and has a chilled peripheral crust or shell which is uniform in thickness and free from latent as well as visible defects or imperfections. 75

To accommodate the detection and measuring of the contraction of the cooling peripheral crust or shell of the casting, the surrounding wall of the chill-chamber 12 is provided in suitable proximity to the upper and 80 lower ends of the chill (see Fig. 1) with holes 20, which are spaced circumferentially of the chill and connect with one of the grooves or chamber enlargements *b*, which holes extend from between the sloping walls of the connected groove or chamber enlargement *b* to the exterior surface of the chill and are gradually reduced at their inner ends toward the connected chamber enlargements. The outer end portion of each hole 20 is screw-threaded, and a correspondingly externally threaded plug *G* is screwed into the said hole, which plug has an inner tapering end fitting the inwardly-tapering end of the hole. It will be observed, therefore, that the chill 90 of my improved mold is provided with suitably-spaced holes 20, with each hole connecting with one of the grooves or chamber enlargements *b* of the chill and normally closed by a plug *G*, which is removable to accommodate the application through the said hole of a graduated instrument or gage for measuring the vertical as well as the horizontal contraction of the casting being formed in the chill during the operation of the mold. In other 95 words, the surrounding wall of the chamber 12 is provided with vertically-spaced beads 100 17, extending circumferentially of the chamber, and the chill is provided with suitably-spaced and suitably-closed gage-receiving 105 holes, with each hole extending from the exterior of the chill to the said chamber between two adjacent beads. 110

To accommodate a sinking or lowering of the crust or shell of the casting formed in and 115 by the mold, a depressible and preferably sand-covered metal ring *K* (see Figs. 1, 4, and 5) is arranged externally of and surrounds the upper end of the drag-cavity 10 and is embedded in the surrounding wall or 120 walls 15 of the said cavity. The ring *K* is adjustable vertically, as will hereinafter appear, and is suitably arranged in under the outer portion of the chill-chamber 12, extending circumferentially of the lower end of 125 the said chamber. The ring *K* is preferably provided on top with upwardly-tapering lugs *k*, projecting upwardly into close proximity to the chamber 12. The ring *K* is provided in its under side with an annular recess 130

22, which consequently extends circumferentially of the ring, and the surrounding wall or walls 15 of the cavity 10 are provided in under the recess 22 with a cavity 23, which is arranged in registry with and extends along the recess 22. The cavity 23 is occupied by fine loose sand or other readily-displaceable loose material 24. The ring K is arranged above the inlet 16 and between the cavity 23 and the lower end of the chill-chamber 12, and a plate or partition l is embedded in the wall of loam or sand between the inlet 16 and the cavity 23. The ring K is provided externally with several laterally and outwardly projecting lugs 25, which are spaced circumferentially of the ring, with the upper surface 26 of each lug 25 sloping downwardly and outwardly and with the lower surface 27 of the said lug sloping upwardly and outwardly. In other words, the upper and lower surfaces 26 and 27 of each lug 25 (see Fig. 1) converge toward the outer or free end of the lug. It will be observed, therefore, that the ring K is provided at suitable intervals circumferentially of the ring with upper and lower surfaces which converge outwardly.

Means for exerting pressure downwardly upon the lugs 25, and consequently downwardly upon the ring K, are provided (see Figs. 1, 4, and 8) and comprise screws f, which extend into engagement with the upper sloping surfaces 26 of the lugs through correspondingly-screw-threaded holes 28, formed in the drag-casing D.

Means for elevating the ring K are provided (see Figs. 1, 5, and 8) and preferably comprise screws h, extending into engagement with the lower sloping surfaces 27 of the lugs 25 through correspondingly threaded holes 30, formed in the drag-casing D. It will be observed that the screws f and h constitute endwise shiftable members which are adapted to coöperate freely with the sloping surfaces 26 and 27 of the ring K in vertically adjusting the ring. By turning the screws f and h in the direction required to shift the upper screws f inwardly and the lower screws h outwardly the ring K is lowered. By turning the said screws in the direction required to actuate the lower screws h inwardly and the upper screws f outwardly the ring K is raised.

Means for exerting any necessary pressure downwardly upon the upper end of the contracting crust or shell of the casting formed in the chill is provided and comprises, preferably, a vertically-arranged pressure-exerting ring m, which (see Figs. 1 and 3) is arranged externally of and surrounds the lower end of the cope-chamber 13. The ring m is embedded in the lower end of the surrounding wall or walls of the chamber 13 and is depressible by pressure exerted downwardly upon the upper end of the ring. The ring m

is provided externally with laterally-projecting and outwardly-tapering lugs 32, which are embedded in the loam or sand of the surrounding wall or walls of the chamber 13 and are instrumental in preventing the descent of the said ring by gravity, but do not prevent the lowering of the ring by pressure exerted downwardly upon the upper end of the ring. The ring m is beveled at its lower end, as at 33, (see Fig. 7,) being preferably provided with a laterally and outwardly facing beveled edge at the said end, with the said edge provided with circumferentially-spaced downwardly-projecting lugs 34. The ring m is turned off internally in a lathe to render the inner surface of the ring smooth and to cause the internal diameter of the ring to gradually decrease toward the lower end of the ring, so as to render the ring upon being pressed downwardly capable of readily freeing itself from the loam or sand. The ring m is beveled at its lower end to avoid any material participation of the said ring in the cooling or chilling of the casting formed in the chill. The ring m has the dimensions and arrangement required to render it capable of being lowered into the chill-chamber 12.

The surrounding wall or walls of the cope-chamber 13 are provided externally of the said chamber with pockets 35, which are spaced circumferentially of the chamber and arranged far enough above the chill to accommodate the interposition of the ring m between the chill and the lower ends of the said pockets. The pockets 35 extend upwardly to the upper extremity of the surrounding wall or walls of the chamber 13.

Vertically-arranged gagers n are preferably embedded in the loam or sand of the surrounding wall or walls of the cope-chamber 13 internally of the pressure-exerting ring m and extend from the lower end or ends of the said wall or walls upwardly a suitable distance, being suitably spaced circumferentially of the said chamber. The surrounding wall or walls of the chamber 13 above the level L, (indicated by dotted line in Fig. 1,) to which the molten metal in pouring the mold is permitted to rise into the cope are provided with lateral holes 36, which are spaced circumferentially of the said chamber and connect the pockets 35 with the said chamber. Four pockets 35 are formed in the cope of the mold illustrated, and consequently the surrounding wall or walls of the chamber 13 is provided with four holes 36, establishing communication between the said chamber and the said pockets. (See Figs. 1 and 2.) Two of the holes 36 are arranged somewhat higher than the remaining two holes 36, so that in pouring molten metal into the chamber 13 in the feeding-head-forming cope from above the upper end of the said chamber for the purpose of raising the level of molten metal in the cope or feed-

ing-head, molten metal will flow from the said chamber first through the lower holes 35 into the connected pockets. The two upper holes 35, as well as the two lower holes 35, are 5 preferably arranged diametrically opposite each other.

Within each pocket 35 is a vertically-arranged calorically-expansible upwardly-tapering metal rod Q, which rests upon the 10 pressure-exerting ring m and preferably has a lower tapering end projecting somewhat into the upper end of the said ring. An abutment-forming plate, block, or weight R is arranged above the cope and extends over 15 the upper ends of the rods Q and prevents or limits upwardly endwise expansion of the said rods, but wedges w (see Fig. 1) are preferably interposed between the upper ends of the rods Q and the abutment R.

20 The cope-casing E (see Fig. 1) is provided at its upper end and externally with a laterally and outwardly projecting annular flange e, and the weight or abutment R extends over and circumferentially of the said flange.

25 The weight or abutment R is provided above the flange e and in its upper side with pockets or recesses 40, which are spaced circumferentially of the cope, and the bottoms of the said recesses are provided with vertically-arranged bolt-holes 42, which register with correspondingly - arranged bolt - holes 43, formed in the flange e. Bolts s extend loosely through the bolt-holes 42 and 43 and through and a suitable distance above the recesses 40.

30 The bolts s are arranged with their heads at the under side of the flange e, and nuts t are mounted on the bolts above the weight or abutment R. Washers u are arranged on the bolts s at the inner ends of the nuts t, and 35 spiral springs x are confined on the bolts within the recesses 40 between the washers u and the bottoms of the said recesses.

It will be observed that the bolts s and nuts t are instrumental in attaching the weight or abutment R to the cope-casing E and the 45 springs x cushion the abutment R against any undue pressure exerted upwardly against the under side of the abutment. The abutment R is adjusted vertically by the proper manipulation of screws y, which are arranged over the cope-casing E and spaced circumferentially of the cope and extend through correspondingly-threaded holes 45, formed in the abutment R into engagement with the upper 50 end of the said casing.

It is obvious that the heating of the rods Q by molten metal poured into the pockets containing the said rods will result in the expansion of the rods, and upward expansion of the 60 said rods being prevented or limited by the abutment R the rods will necessarily expand downwardly, and thereby exert pressure downwardly upon the ring m to effect a lowering of the said ring and the exertion of pressure by the said ring downwardly upon the

cooling peripheral crust or shell of the casting formed in the chill.

The weight or abutment R (see Fig. 1) is provided centrally with a circular opening r to accommodate the pouring of molten metal 70 centrally of the said abutment into the upper end of the cope-chamber 13.

Cutters or cut-offs 46, formed by metal plates coated with blacking, are provided for closing the holes 36, and thereby cutting the 75 connections at the said holes between the molten metal in the cope-chamber 13 and the metal run into the pockets 35. (See Figs. 1 and 2.) The cut-offs 46 are normally open and preferably arranged vertically within the 80 surrounding wall or walls of the cope-chamber 13 above the said holes.

The opening r in the weight or abutment R is larger diametrically than the cope-chamber 13, so as to accommodate the projection 85 of the cut-offs 46 upwardly into the said opening through which the said cut-offs are accessible.

To prevent the loam or sand forming the surrounding wall or walls of the cope-chamber 90 from being broken around the cut-offs 46 from any cause, (see Figs. 1 and 2,) sheath-forming metal tubes 50 surround the cut-offs and are embedded within the said wall or walls, said tubes extending from the upper 95 end of the cope into suitable proximity to the holes 36, as shown in Fig. 1.

To prevent the molten metal which is run into the pockets 35 at the holes 36, during the heating of the rods Q in the said pockets, 100 from pouring against the rods opposite the said holes, shields 47 (see Figs. 1 and 2) are attached to and extend circumferentially of the rods, which shields are arranged between the rods and the said holes directly opposite 105 the holes. Within each pocket 35 is arranged a metal plate or partition 52 at the outer side of the rod Q in the said pocket, which partition is arranged radially of the outer portion of the pocket and extends from 110 end to end of the pocket.

By the construction hereinbefore described it will be observed that means are provided for exerting pressure downwardly upon the contracting crust or shell of the casting 115 formed in the chill, that the said shell or crust is held in contact with the downwardly or inwardly sloping bottom walls of the grooves or chamber enlargements in the chill until the casting has contracted enough to become free from the said chamber enlargements, and that the said crust or shell can be automatically depressed or lowered after the pouring of the mold and maintained in contact with the aforesaid sloping walls and exactly central relative to the chill during the contraction of the said shell or crust. I would also remark that to prevent the molten metal run into the pockets 35 to expand the rods Q from coming in direct contact with 125 130

the ring *m* and with the tapered lower ends of the rods the bottoms of the said pockets are preferably covered with a layer or body of fine sand *J*, which surrounds and incloses the 5 said ends of the said rods.

Briefly described, the operation of my improved mold is as follows: The molten metal employed in casting a roll is introduced at the inlet 16 of the drag *A* into the cavity 10, filling the said cavity and then rising into and filling the chill-chamber 12 and then rising into the cope-chamber 13 until the level of the molten metal within the said cope-chamber has risen into suitable proximity to the 10 lower holes 36, as indicated by the dotted line *L* in Fig. 1. The molten metal introduced into the mold is then permitted to stand until the chill has formed a crust or shell which can be operated upon, whereupon 15 the molten metal is introduced into the upper end of the cope-chamber through the opening *r* in the weight or abutment *R* to a level a suitable distance above the upper holes 36, so that molten metal flows from the cope- 20 chamber 13 first through the lower holes 36 into the pockets 35, connected with the said holes and then, if required, through the upper holes 36 into the pockets 35, connected with the last-mentioned holes and heats the 25 30 calorically-expansible rods *Q* in the said pockets. Upward expansion of the rods *Q* is prevented or limited by the weight or abutment *R*, as already indicated, and consequently the heating of the rods *Q* expands them downwardly and uniformly, resulting 35 in the exertion of pressure downwardly upon the pressure-exerting ring *m*, which in turn presses down upon the cooling and contracting crust or shell of the roll-body being cast 40 in the chill.

It will be observed that by means of the location of two of the holes 36 above the remainder of the said holes the ring *m* can be depressed at two different times and twice as 45 far as by having all of the said holes arranged in the same horizontal plane because after the calorically-expansible rods in the pockets connected with the lower holes 36 have exerted their pressure upon the ring *m* the 50 wedges *w* at the upper ends of the other rods are tightened, so that the subsequent heating and expansion of the calorically-expansible rods in the pockets connected with the upper holes 36 will result in a second or further depression or lowering of the ring *m*. As the 55 said shell or crust is pressed downwardly it keeps in contact with the downwardly and inwardly sloping bottom walls of the grooves or chamber enlargements *b* in the chill, and consequently a constant pressure on the 60 contracting shell or crust is maintained until the contraction has progressed far enough to permit the external ribs or beads formed on the casting to slide down the aforesaid walls. 65 Obviously the upper of two adjacent ribs or

beads formed on the casting will lower somewhat more during the contraction of the casting than the lower of the said ribs or beads, and to accommodate this unequal lowering of the external ribs or beads formed on 70 the casting the importance of the gradual increase in the slope of the bottom walls of the grooves or chamber enlargements toward the upper end of the chill is apparent. I would also remark that the provision of the chill 75 with the grooves *b*, having downwardly and inwardly sloping top and bottom walls, is also not unimportant to more thoroughly break up the cakish or sluggish metal. The molten metal becomes more dull or sluggish 80 as it ascends within the chill, and a greater slope of the bottom walls of the grooves *b* facilitates the passage of the material into and outwardly in the grooves. Therefore because the molten metal becomes more sluggish 85 as it ascends another advantage in a gradual increase of the slope in the bottom walls in the grooves toward the upper end of the chill becomes obvious since such increase in the said slope increases the facility with 90 which the sluggish molten metal can work outwardly into the grooves.

The undercut top walls of the grooves *b* accommodate the passage of air and gases into the upper portions of the said grooves 95 and the blacking contained in the said grooves after applying blacking to the said walls—that is, air and gases are permitted to escape from the molten metal into the upper portions of the grooves *b* before the molten metal which is to form the outer crust or shell of the casting has become solid enough to prevent the escape of air and gases from the molten metal—and of course as the ribs or beads formed on the said shell or crust within 100 the said grooves are cut away in dressing the roll after the casting operation mutilation of or imperfections in the said beads or ribs by the air and gases entrapped in the grooves is of no consequence. The molten metal does 105 not of course solidify instantly, and enough time is required for the solidification of the molten metal in the grooves *b* to permit gases to escape from the body of molten metal into the upper portions of the said grooves. The 110 undercut top walls of the grooves *b* also assist in causing the coating of blacking or surface-coating generally used in coating the interior surfaces of chills to adhere firmly to the chill. The top wall of each groove *b* is at an acute 115 angle to the inwardly-facing central wall of the groove, and consequently in applying the blacking or surface-coating by means of a brush to the said wall the corner formed between the walls is more or less filled, so as to 120 form a web of blacking or surface-coating which bridges the space between the said walls at the said corner and materially assists in holding the blacking or coating to the 125 remaining portions of the said walls. 130

The ring K permits the settling or lowering of the contracting shell or crust of the casting being formed in the chill, the said ring being lowered by a proper manipulation of the ring-engaging screws f and h, as already indicated, and readily accommodated and facilitated by the loose sand or readily displaceable material within the cavity 23, entering the recess 22, formed in the bottom of the said ring during the lowering of the said ring. The ring K is of course lowered after the mold has been poured and the molten metal which is to form the outer crust or shell of the casting has begun to contract during the solidification of the casting, so that the ribs or beads formed on the said shell or crust within the grooves b are kept in contact with the bottom walls of the grooves.

Any further depression or lowering of the casting after the expansion-rods Q have performed their function is done by operating the wedges w with or without a further manipulation of the screws y and nuts t against the action of the rings x, which prevent the exertion of any undue and detrimental pressure on the casting.

The cutters or cut-offs 46 are depressed immediately upon the supplying of the pockets 35 with the desired quantity of molten metal, so as to avoid any solid connection between the metal in the pockets with the metal left in the feeding-head or cope-chamber 13, and thereby afford to the upper neck and trunnion of the roll being cast the desired freedom to follow downwardly during the natural vertical contraction of the casting.

After the operation of the mold the rods Q and adhering solidified metal with the shields 47 and plates 52 are withdrawn from the cope, whereupon the plates 52 are separated from the rods and adhering metal which can thereupon be readily loosened relative to the rods by wedges or other spreading means inserted into the spaces left unoccupied by the separation of the said plates.

I would also remark that there are cases—as, for instance, in casting very long rolls and in casting rolls having large necks and relatively small bodies—when it may be desirable to lower or depress the whole upper neck, sand-body of the cope, and the entire upper portion of the casting, as well as the chilled crust or shell of the body of the roll. In such cases the cutters or cut-offs 46 and shields 50 can be left out of the cope, so that the metal in the holes 36 will unite solidly with the feeding-head or upper portion of the casting and the castings formed in the pockets 35, whereby any expansion of the calorically-expansible rods Q would then force downwardly all of the casting above the upper end of the chill. In these cases the sand J would be omitted, so that the metal flowing into the pockets 35 could get to and around

the tapered lower ends of the rods Q, and thereby cause the casting formed in the pockets 35 to be depressed along with the ring m, and thereby force and crush downwardly the sand-walls of the cope-chamber or feeding-head and exert a downward pressure upon the whole upper portion of the roll-forming casting.

What I claim is—

1. In a mold for casting a chilled roll, a vertically-arranged chill provided interiorly with a cylindrical chamber extending from the upper end to the lower end of the chill, with the surrounding wall of the chamber provided with vertically-spaced grooves extending circumferentially of the chamber, with the top and bottom walls of the grooves sloping downwardly and inwardly, and with the slope of the bottom wall of the lower of two adjacent grooves less than the slope of the bottom wall of the upper of the said grooves.

2. In a roll-casting mold, a vertically-arranged annular chill provided interiorly with vertically-spaced grooves extending circumferentially of the chill, with the top and bottom walls of the grooves sloping downwardly and inwardly.

3. In a roll-casting mold, a vertically-arranged chill provided interiorly with a cylindrical chamber extending from the upper end to the lower end of the chill, with the surrounding wall of the chamber provided with vertically-spaced grooves extending circumferentially of the chamber, with the bottom walls of the grooves sloping downwardly and inwardly, and with the slope of the bottom wall of the lower of two adjacent grooves less than the slope of the bottom wall of the upper of the said grooves.

4. In a roll-casting mold, a vertically-arranged chill provided interiorly with a chamber which extends from the upper end to the lower end of the chill and is enlarged diametrically at suitable intervals between the ends of the chill, with the bottom walls of the diametrical enlargements of the chamber sloping downwardly and inwardly and having a greater slope in the upper portion than in the lower portion of the chill.

5. In a roll-casting mold, a vertically-arranged chill provided interiorly with a chamber which extends from the upper end to the lower end of the chill and is enlarged diametrically at suitable intervals between the ends of the chill, with the bottom walls of the diametrical enlargements of the chamber sloping downwardly and inwardly, and with the slopes of the bottom walls of the said chamber enlargements being greater at the upper end of the chill and gradually decreasing toward the lower end of the chill.

6. In a roll-casting mold, a vertically-arranged annular chill provided interiorly with vertically-spaced grooves extending circum-

ferentially of the chill, with the bottom walls of the grooves sloping downwardly and inwardly, with the slope of the bottom wall of the lower of two adjacent grooves less than the slope of the bottom wall of the upper of the said grooves, and with the bead formed between the said adjacent grooves rounded at the junction of the face of the bead with the top wall of the lower of the said grooves.

10. 7. In a roll-casting mold, an upright chill provided interiorly with a chamber which extends from the upper end to the lower end of the chill and is enlarged diametrically at suitable intervals between the ends of the chill, with the diametrical enlargements of the chamber extending circumferentially of the chill, with the top and bottom walls of the said chamber enlargements sloping downwardly and inwardly, and the chill being provided with holes spaced circumferentially of and connecting with one of the aforesaid chamber enlargements, with each hole arranged between the top and bottom walls of the connected chamber enlargements and extending from the said chamber enlargements to the exterior of the chill and gradually reduced at its inner end toward the connected chamber enlargement, and plugs occupying and removable from the said holes and having their inner ends tapering and fitting the inner ends of the holes.

8. In a roll-casting mold, an upright chill provided interiorly with a chamber which extends from the upper end to the lower end of the chill and is enlarged diametrically at suitable intervals between the ends of the chill, with the diametrical enlargements of the chamber extending circumferentially of the chill, and the chill being provided with a lateral hole connected with one of the aforesaid chamber enlargements, which hole extends from the connected chamber enlargement to the exterior of the chill and is gradually reduced at its inner end toward the connected chamber enlargement, and a plug occupying and removable from the said hole and having its inner end tapering and fitting the inner end of the hole.

9. In a roll-casting mold, an upright chill provided interiorly with a chamber which extends from the upper end to the lower end of the chill and is enlarged diametrically at suitable intervals between the ends of the chill, with the diametrical enlargements of the chamber extending circumferentially of the chill, and the chill being provided with holes spaced circumferentially of and connecting with one of the aforesaid chamber enlargements, which holes extend from the connected chamber enlargement to the exterior of the chill, and plugs occupying and removable from the said holes.

10. In a roll-casting mold, an upright chill provided interiorly with a chamber which extends from the upper end to the lower end of

the chill, with the surrounding wall of the chamber provided with suitably-spaced holes, which holes extend from the chamber to the exterior surface of the chill and are gradually reduced at their inner ends toward the chamber, with the surrounding wall of the outer portion of each hole screw-threaded, and correspondingly-threaded plugs screwed into the said holes and having their inner ends tapering and fitting the inner ends of the holes.

11. In a roll-casting mold, an upright chill provided interiorly with a chamber which extends from the upper end to the lower end of the chill and is enlarged diametrically at suitable intervals between the ends of the chill, with the diametrical enlargements of the chamber extending circumferentially of the chill, and the chill being provided in both its upper and lower portions with holes spaced circumferentially of and connecting with one of the aforesaid chamber enlargements, which holes extend from the connected chamber enlargements to the exterior of the chill, and removable plugs for closing the said holes.

12. In a roll-casting mold, an upright chill provided interiorly with a chamber which extends from the upper end to the lower end of the chill and is enlarged diametrically at suitable intervals between the ends of the chill, with the diametrical enlargements of the chamber extending circumferentially of the chill, and with the top and bottom walls of the said chamber enlargements sloping downwardly and inwardly, and the chill being provided with vertically-spaced holes connecting with one of the aforesaid chamber enlargements of the chamber, which holes extend from the connected chamber enlargements to the exterior of the chill, and removable plugs for closing the said holes.

13. In a roll-casting mold, a chill provided interiorly with a chamber and having a hole extending laterally from the chamber to the exterior of the chill, which hole is gradually reduced at its inner end toward the chamber, and a removable plug having a tapering end fitting the inner end of the said hole.

14. In a roll-casting mold, the combination, with a lower mold part or drag, and a vertically-arranged chill provided interiorly with a cylindrical chamber extending from the upper end to the lower end of the chill, with the surrounding wall of the chamber provided with vertically-spaced grooves extending circumferentially of the chamber, with the bottom walls of the grooves sloping downwardly and inwardly, and with the drag provided with a cavity having an inlet for molten metal and arranged centrally of and diametrically smaller than but in communication with the aforesaid chamber, with the surrounding wall or walls of the said cavity formed by a body of loam or molding-

sand, of a depressible sand-covered ring embedded in the said wall or walls and surrounding the said cavity; means instrumental in depressing the ring, and means 5 instrumental in elevating the ring.

15. In a roll-casting mold, the combination, with a lower mold part or drag, and a vertically-arranged chill provided interiorly with a cylindrical chamber extending from 10 the upper end to the lower end of the chill, with the surrounding wall of the chamber provided with vertically-spaced grooves extending circumferentially of the chamber, with the bottom walls of the grooves sloping 15 downwardly and inwardly, with the drag provided with a cavity which has an inlet for molten metal and is arranged centrally of and diametrically smaller than but in communication with the aforesaid chamber, and 20 with the surrounding wall or walls of the cavity formed by a body of loam or molding-sand, of a vertically-adjustable sand-covered ring embedded in the said wall or walls and surrounding the said cavity.
25. 16. In a roll-casting mold, the combination, with a lower mold part or drag, and a vertically-arranged chill provided interiorly with a chamber extending from the upper end to the lower end of the chill, with the drag 30 provided with a cavity which has an inlet for molten metal and is arranged centrally of and diametrically smaller than but in communication with the aforesaid chamber, with the surrounding wall or walls of the cavity formed 35 by a body of loam or molding-sand, of a vertically-adjustable ring embedded in the said wall or walls and surrounding the said cavity, which ring is provided in its under side with a recess extending circumferentially of the 40 ring, and the aforesaid wall or walls being provided in under the said recess with a cavity occupied by loose sand or displaceable material and arranged in registry with and extending along the recess in the ring.
45. 17. In a roll-casting mold, the combination, with a lower mold part or drag, and a vertically-arranged chill provided interiorly with a chamber extending from the upper end to the lower end of the chill, with the 50 drag provided with a cavity arranged centrally of and diametrically smaller than but in communication with the aforesaid chamber, with the surrounding wall or walls of the said cavity formed by a body of loam or 55 molding-sand and provided at one side and a suitable distance below the upper end of the cavity with an inlet for molten metal, of a vertically-adjustable ring embedded in the said wall or walls above the said inlet and surrounding the aforesaid cavity, and a plate or 60 partition embedded in the loam or sand of the drag and arranged above the aforesaid inlet and a suitable distance below the ring.
65. 18. In a roll-casting mold, the combination, with a lower mold part or drag, and a

chill provided interiorly with a chamber extending from the lower extremity of the chill upwardly, with the drag provided with a cavity which has an inlet for molten metal and is in communication with the said chamber, of 70 a depressible member arranged externally and extending circumferentially of the aforesaid cavity, said depressible member being in position to form a bearing for the lower end of the outer shell or crust of the casting during 75 the lowering of the latter.

19. In a roll-casting mold, the combination, with a lower mold part or drag, and a vertically-arranged chill provided interiorly with a chamber extending from the upper end 80 to the lower end of the chill, with the drag provided centrally with a cavity which has an inlet for molten metal and is arranged centrally of and diametrically smaller than but in communication with the aforesaid chamber, of a 85 depressible ring arranged in under the said chamber and surrounding the aforesaid cavity and provided below the chamber in the chill with upwardly-projecting upwardly-tapering lugs, means instrumental in depressing 90 the ring, and means instrumental in elevating the ring.

20. In a roll-casting mold, the combination, with the lower mold part or drag and a vertically-arranged chill arranged over the 95 drag and provided interiorly with a chamber extending from the upper end to the lower end of the chill, with the drag provided with a cavity which has an inlet for molten metal and is arranged centrally of and diametrically 100 smaller than but in communication with the aforesaid chamber, of a depressible ring arranged in under the said chamber and surrounding the aforesaid cavity; means for exerting pressure downwardly upon the ring to 105 depress the ring, and means for exerting pressure upwardly against the ring to elevate the ring.

21. In a roll-casting mold, the combination, with the lower mold part or drag and a vertically-arranged chill arranged over the drag and provided interiorly with a chamber extending from the upper end to the lower end of the chill, with the drag provided with a cavity which has an inlet for molten metal 110 and is arranged centrally of and diametrically smaller than but in communication with the aforesaid chamber, of a depressible ring arranged in under the said chamber and surrounding the aforesaid cavity, and means 115 whereby the ring may be depressed.

22. In a roll-casting mold, the combination, with the lower mold part or drag, and a vertically-arranged chill provided interiorly with a chamber extending from the upper 120 end to the lower end of the chill, with the drag provided with a cavity which has an inlet for molten metal and is arranged centrally of and diametrically smaller than but in communication with the aforesaid chamber, with 125

130

the surrounding wall or walls of the said cavity formed by a body of loam or molding-sand surrounded by a metal casing, of a depressible ring arranged in under the aforesaid 5 chamber and surrounding the said cavity; screws extending through correspondingly-threaded holes formed in and spaced circumferentially of the aforesaid casing, which screws are arranged to exert pressure downwardly upon the ring; screws extending through correspondingly-threaded holes formed in and spaced circumferentially of the said casing, with the last-mentioned screws arranged to exert pressure upwardly against 10 the ring, and the ring being provided with upwardly and outwardly sloping surfaces engaged by the last-mentioned screws and with downwardly and outwardly sloping surfaces engaged by the first-mentioned screws.

20 23. In a roll-casting mold, the combination, with the lower mold part or drag, and a vertically-arranged chill provided interiorly with a chamber extending from the upper end to the lower end of the chill, with the 25 drag provided with a cavity which has an inlet for molten metal and is arranged centrally of and diametrically smaller than but in communication with the aforesaid chamber, with the surrounding wall or walls of the said cavity formed by a body of loam or molding-sand surrounded by a metal casing, of a depressible ring arranged in under the aforesaid chamber and surrounding the said cavity; screws extending through correspondingly- 30 threaded holes formed in and spaced circumferentially of the said casing, which screws are arranged to exert pressure downwardly upon the ring, and the ring being provided with downwardly and outwardly sloping surfaces engaged by the said screws.

24. In a roll-casting mold, the combination, with the lower mold part or drag, and a vertically-arranged chill provided interiorly with 35 a chamber extending from the upper end to the lower end of the chill, with the drag provided with a cavity having an inlet for molten metal and arranged centrally of and diametrically smaller than but in communication with the aforesaid chamber, with the surrounding wall or walls of the said cavity formed by a body of loam or molding-sand surrounded by a metal casing, of a depressible ring arranged in under the aforesaid 40 chamber and surrounding the said cavity; means for depressing the ring, and screws extending through correspondingly-threaded holes formed in and spaced circumferentially of the said casing, which screws are arranged to exert pressure upwardly against the ring, and the ring being provided with upwardly and outwardly sloping surfaces engaged by the said screws.

25. In a roll-casting mold, the combination, with the lower mold part or drag, and a

vertically-arranged chill provided interiorly with a chamber extending from the upper end to the lower end of the chill, with the drag provided with a cavity having an inlet for molten metal and arranged centrally of and diametrically smaller than but in communication with the aforesaid chamber, of a depressible ring arranged in under the aforesaid chamber and surrounding the aforesaid cavity and provided with laterally and outwardly projecting lugs spaced circumferentially of the ring, and means adapted to adjust the ring vertically and comprising members engaging the upper and lower surfaces of the aforesaid lugs.

26. In a roll-casting mold, the combination, with an upright chill provided interiorly with a chamber extending from the upper end to the lower end of the chill, of a depressible ring arranged in under the aforesaid chamber and provided with laterally and outwardly projecting lugs spaced circumferentially of the ring, with the upper and lower surfaces of each lug converging toward the outer or free end of the lug, and means adapted to adjust the ring vertically and comprising members engaging the sloping surfaces of the aforesaid lugs.

27. In a roll-casting mold, the combination, with an upright chill provided interiorly with a chamber extending from the upper end to the lower end of the chill, of a depressible ring arranged in under the aforesaid chamber and provided with laterally and outwardly projecting lugs spaced circumferentially of the ring, with the upper and lower surfaces of each lug sloping and converging toward the outer or free end of the lug, suitably-supported endwise-shiftable members engaging the upper sloping surfaces of the lugs, and suitably-supported endwise-shiftable members engaging the lower sloping surfaces of the lugs.

28. In a roll-casting mold, the combination, with an upright chill provided interiorly with a chamber extending from the upper end to the lower end of the chill, of a suitably-supported depressible ring arranged in under the aforesaid chamber and provided with laterally and outwardly projecting lugs spaced circumferentially of the ring, with the upper surfaces of the lugs sloping downwardly and outwardly, and suitably-supported endwise-shiftable members engaging the said sloping surfaces of the lugs.

29. In a roll-casting mold, the combination, with an upright chill provided interiorly with a chamber which extends from the lower end of the chill upwardly, of a suitably-supported depressible ring arranged in under the said chamber and provided with laterally and outwardly projecting lugs spaced circumferentially of the ring, with the lower surfaces of the lugs sloping upwardly and outwardly; suitably-supported endwise-shiftable mem-

130

bers engaging the said sloping surfaces of the lugs, and means for depressing the ring.

30. In a roll-casting mold, the combination, with an upright chill provided interiorly with a chamber extending from the upper end to the lower end of the chill, of a suitably-supported compressible ring arranged in under the aforesaid chamber, and members overlapping and arranged to depress the ring.

10 31. In a roll-casting mold, the combination, with a chill provided interiorly with a chamber extending from the lower end of the chill upwardly, of means whereby the outer crust or shell of the casting formed in the chill
15 can be made to descend into a lower position.

32. In a roll-casting mold, the combination, with a lower mold part or drag, and a chill arranged over the drag and provided interiorly with a chamber which extends from the upper end to the lower end of the chill and is enlarged laterally at suitable intervals between the ends of the chill, with the lateral enlargements of the said chamber extending circumferentially of the chill, with the bot-

25 circumferentially of the chill, with the bottom walls of the said chamber-enlargements sloping downwardly and inwardly, and with the drag provided with a cavity which has an inlet for molten metal and is arranged centrally of and diametrically smaller than but 30 in communication with the aforesaid chill-chamber, of a vertically-adjustable ring arranged in under the chill-chamber and surrounding the aforesaid cavity; an upper mold part or cope arranged over the chill and provided interiorly with a chamber which is arranged centrally of and diametrically smaller than but 35 in communication with the chill-chamber, with the surrounding wall or walls of the cope-chamber formed by a body of 40 loam or molding-sand and provided with pockets arranged externally and spaced circumferentially of the said chamber a suitable distance above the chill, said wall or walls having holes connecting the said pockets 45 with the cope-chamber; a pressure-exerting ring embedded within the lower end of the aforesaid wall or walls below the pockets and having the dimensions and arrangement required to render it capable of being lowered 50 into the chill-chamber; calorically-expansible upright rods arranged within the pockets and resting upon the said ring, and an abutment for the upper ends of the rods.

for the upper ends of the rods.

33. In a roll-casting mold, the combination, with a lower mold part or drag, and a chill arranged over the drag and provided interiorly with a chamber which extends from the upper end to the lower end of the chill and is enlarged laterally at suitable intervals between the ends of the chill, with the lateral enlargements of the said chamber extending circumferentially of the chill, with the bottom walls of the said chamber enlargements sloping downwardly and inwardly, and with the drag provided with a cavity which has an

inlet for molten metal and is arranged centrally of and diametrically smaller than but in communication with the aforesaid chill-chamber, of a vertically-adjustable ring arranged in under the chill-chamber and surrounding the aforesaid cavity; an upper mold part or cope arranged over the chill and provided interiorly with a chamber which is arranged centrally of and diametrically smaller than but in communication with the chill-chamber, with the surrounding wall or walls of the cope-chamber formed by a body of loam or molding-sand and provided with pockets arranged externally and spaced circumferentially of the said chamber a suitable distance above the chill; a pressure-exerting ring embedded within the lower end of the aforesaid wall or walls below the pocket and having the dimensions and arrangement required to render it capable of being lowered into the chill-chamber; calorically-expansible upright rods arranged within the pockets and resting upon the said ring, and an abutment for the upper ends of the rods.

34. In a roll-casting mold, the combination, with a lower mold part or drag, and a chill arranged over the drag and provided interiorly with a chamber which extends from the upper end to the lower end of the chill and is enlarged laterally at suitable intervals between the ends of the chill, with the lateral enlargements of the said chamber extending circumferentially of the chill, with the bottom walls of the said chamber enlargements sloping downwardly and inwardly, and with the drag provided with a cavity which has an inlet for molten metal and is arranged centrally of and diametrically smaller than but in communication with the aforesaid chill-chamber, of a vertically-adjustable ring arranged in under the chill-chamber and surrounding the aforesaid cavity; an upper mold part or cope arranged over the chill and provided interiorly with a chamber which is arranged centrally of and diametrically smaller than but in communication with the chill-chamber, with the surrounding wall or walls of the cope-chamber formed by a body of loam or molding-sand and provided with pockets arranged externally and spaced circumferentially of the said chamber a suitable distance above the chill, said wall or walls also having holes connecting the said pockets

also having holes connecting the said pockets with the cope-chamber; a pressure-exerting ring embedded within the lower end of the aforesaid wall or walls below the pockets and having the dimensions and arrangement required to render it capable of being lowered into the chill-chamber; calorically-expansible upright rods arranged within the pockets and resting upon the said ring; an abutment for the upper ends of the rods, and shields arranged within the pockets between the rods and the aforesaid holes and attached to the rods. 130

35. In a roll-casting mold, the combination, with a lower mold part or drag, and a chill arranged over the drag and provided interiorly with a chamber which extends from the upper end to the lower end of the chill and is enlarged laterally at suitable intervals between the ends of the chill, with the lateral enlargements of the said chamber extending circumferentially of the chill, with the bottom walls of the said chamber enlargements sloping downwardly and inwardly, and with the drag provided with a cavity which has an inlet for molten metal and is arranged centrally of and diametrically smaller than but in communication with the aforesaid chill-chamber, of a vertically-adjustable ring arranged in under the chill-chamber and surrounding the aforesaid cavity; an upper mold part or cope arranged over the chill and provided interiorly with a chamber which is arranged centrally of and diametrically smaller than but in communication with the chill-chamber; compressible upright rods arranged within the surrounding wall or walls of the cope-chamber and spaced circumferentially of the said chamber a suitable distance above the chill, and a suitably-supported compressible pressure-exerting ring arranged within the lower end of the aforesaid wall or walls in under the rods and having the dimensions and arrangement required to render it capable of being depressed into the chill-chamber by the rods.
36. In a roll-casting mold, the combination, with a lower mold part or drag; and a chill arranged over the drag and provided interiorly with a chamber which extends from the upper end to the lower end of the chill and is enlarged laterally at suitable intervals between the ends of the chill, with the lateral enlargements of the said chamber extending circumferentially of the chill, with the bottom walls of the said chamber enlargements sloping downwardly and inwardly and with the drag provided with a cavity which has an inlet for molten metal and is arranged centrally of and diametrically smaller than but in communication with the aforesaid chill-chamber, of a vertically-adjustable ring arranged in under the chill-chamber and surrounding the aforesaid cavity; an upper mold part or cope arranged over the chill and provided interiorly with a chamber which is arranged centrally of and diametrically smaller than but in communication with the chill-chamber; and a suitably-supported pressure-exerting ring arranged within the lower end of the aforesaid wall or walls and having the dimensions and arrangement required to render it capable of being lowered into the chill-chamber, said pressure-exerting ring being compressible independently of the said wall or walls.
37. In a roll-casting mold, the combination, with an upright chill provided interiorly with a chamber which extends from the upper end to the lower end of the chill and is enlarged laterally at suitable intervals between the ends of the chill, with the bottom walls of the chamber-enlargements sloping downwardly and inwardly, of a suitably-supported compressible member arranged in under the said chamber in position to afford bearing to the lower end of the crust or shell of the casting formed within the chill, and means whereby a downward pressure can be exerted upon the upper end of the said shell or crust.
38. In a roll-casting mold, the combination, with a vertically-arranged chill provided interiorly with a chamber extending from the upper end of the chill downwardly, and an upper mold part or cope arranged over the chill and provided interiorly with a chamber which is arranged centrally of but diametrically smaller than and in communication with the aforesaid chill-chamber, with the surrounding wall or walls of the cope-chamber formed by a body of loam or molding-sand and provided with pockets arranged externally and spaced circumferentially of the said chamber a suitable distance above the outer portion of the chill-chamber, said wall or walls also having holes connecting the pockets with the cope-chamber, of a pressure-exerting ring embedded in the lower end of the said wall or walls below the pockets, which ring has the dimensions and arrangement required to render it capable of being lowered into the chill-chamber; calorically-expansible upright rods arranged within the pockets and over the ring, and an abutment overlapping the upper ends of the rods.
39. In a roll-casting mold, the combination, with a vertically-arranged chill provided interiorly with a chamber extending from the upper end of the chill downwardly, and an upper mold part or cope arranged over the chill and provided interiorly with a chamber which is arranged centrally of but diametrically smaller than and in communication with the aforesaid chill-chamber, with the surrounding wall or walls of the cope-chamber formed by a body of loam or molding-sand and provided with pockets arranged externally and spaced circumferentially of the said chamber a suitable distance above the outer portion of the chill-chamber, said wall or walls also having holes connecting the pockets with the cope-chamber, of a pressure-exerting ring embedded in the lower end of the said wall or walls below the pockets, which ring has the dimensions and arrangement required to render it capable of being lowered into the chill-chamber; calorically-expansible upright rods arranged within the pockets and over the ring, and means for preventing or limiting upward expansion of the rods.
40. In a roll-casting mold, the combina-

- tion, with a vertically-arranged chill provided interiorly with a chamber extending from the upper end of the chill downwardly, and an upper mold part or cope arranged over the chill and provided interiorly with a chamber which is arranged centrally of and diametrically smaller than and in communication with the aforesaid chill-chamber, of calorically-expansible upright rods arranged within the surrounding wall or walls of the cope-chambers and spaced circumferentially of the said chamber a suitable distance above the outer portion of the chill-chamber; a suitably-supported depressible pressure-exerting ring in under and in position to be depressed by the rods, which ring has the dimensions and arrangement required to render it capable of being lowered into the chill-chamber, and means for preventing or limiting upward expansion of the rods.
41. In a roll-casting mold, the combination, with a vertically-arranged chill provided interiorly with a chamber extending from the upper end of the chill downwardly, and an upper mold part or cope arranged over the chill and provided interiorly with a chamber which is arranged centrally of but diametrically smaller than and in communication with the aforesaid chill-chamber, with the surrounding wall or walls of the cope-chamber formed by a body of loam or molding-sand and provided externally of the said chamber with calorically-expansible means arranged a suitable distance above the outer portion of the chill-chamber, of a suitably-supported depressible pressure-exerting ring in position to be depressed by the operation of the aforesaid calorically-expansible means, which ring has the dimensions and arrangement required to render it capable of being lowered into the chill-chamber.
42. In a roll-casting mold, the combination, with a vertically-arranged chill provided interiorly with a chamber extending from the upper end of the chill downwardly, and an upper mold part or cope arranged over the chill and provided interiorly with a chamber which is arranged centrally of but diametrically smaller than and in communication with the aforesaid chill-chamber, with the surrounding wall or walls of the cope-chamber formed by a body of loam or molding-sand and provided with pockets arranged externally and spaced circumferentially of the said chamber a suitable distance above the outer portion of the chill-chamber, said wall or walls also having holes connecting the pockets with the cope-chamber, a pressure-exerting ring embedded in the lower end of the said wall or walls below the pockets and having the dimensions and arrangement required to render it capable of being lowered into the chill-chamber; calorically-expansible upright rods arranged within the pockets and in position to depress the ring, and means for preventing upward expansion of the rods.
43. In a roll-casting mold, the combination, with a vertically-arranged chill provided interiorly with a chamber extending from the upper end of the chill downwardly, and an upper mold part or cope arranged over the chill and provided interiorly with a chamber which is arranged centrally of but diametrically smaller than and in communication with the aforesaid chill-chamber, with the surrounding wall or walls of the cope-chamber formed by a body of loam or molding-sand and provided with pockets arranged externally and spaced circumferentially of the said chamber a suitable distance above the outer portion of the chill-chamber, said wall or walls also having holes connecting the pockets with the cope-chamber, of a pressure-exerting ring embedded in the lower end of the said wall or walls below the pockets and having the dimensions and arrangement required to render it capable of being lowered into the chill-chamber; calorically-expansible upright rods arranged within the pockets and projecting into and arranged to depress the ring, and means for preventing upward expansion of the rods.
44. In a roll-casting mold, an upper mold part or cope provided centrally with a chamber for receiving molten metal, with the surrounding wall or walls of the chamber formed by loam or molding-sand and provided with pockets arranged externally and spaced circumferentially of the chamber a suitable distance above the lower end of the cope, said wall or walls having holes connecting the pockets with the chamber; vertically-movable cutters or cut-offs embedded in the wall or walls above the holes and extending upwardly a suitable distance, which cut-offs are normally elevated or open and are adapted to lower to sever the connections between the pockets and the chamber; a suitably-supported pressure-exerting ring arranged externally and extending circumferentially of the chamber below the pockets; upright calorically-expansible rods arranged within the pockets and in position to depress the ring, and means for preventing upward expansion of the rods.
45. In a roll-casting mold, an upper mold part or cope provided centrally with a chamber for receiving molten metal, with the surrounding wall or walls of the chamber formed by loam or molding-sand and provided with pockets arranged externally and spaced circumferentially of the chamber a suitable distance above the lower end of the cope, said wall or walls having holes connecting the pockets with the chamber; cutters or cut-offs arranged to sever the connections between

means for preventing upward expansion of the rods, and shields arranged within the pockets between the holes and the rods and opposite the said holes, which shields are attached to the rods.

70

43. In a roll-casting mold, the combination, with a vertically-arranged chill provided interiorly with a chamber extending from the upper end of the chill downwardly, and an upper mold part or cope arranged over the chill and provided interiorly with a chamber which is arranged centrally of but diametrically smaller than and in communication with the aforesaid chill-chamber, with the surrounding wall or walls of the cope-chamber formed by a body of loam or molding-sand and provided with pockets arranged externally and spaced circumferentially of the said chamber a suitable distance above the outer portion of the chill-chamber, said wall or walls also having holes connecting the pockets with the cope-chamber, of a pressure-exerting ring embedded in the lower end of the said wall or walls below the pockets and having the dimensions and arrangement required to render it capable of being lowered into the chill-chamber; calorically-expansible upright rods arranged within the pockets and projecting into and arranged to depress the ring, and means for preventing upward expansion of the rods.

80

44. In a roll-casting mold, an upper mold part or cope provided centrally with a chamber for receiving molten metal, with the surrounding wall or walls of the chamber formed by loam or molding-sand and provided with pockets arranged externally and spaced circumferentially of the chamber a suitable distance above the lower end of the cope, said wall or walls having holes connecting the pockets with the chamber; vertically-movable cutters or cut-offs embedded in the wall or walls above the holes and extending upwardly a suitable distance, which cut-offs are normally elevated or open and are adapted to lower to sever the connections between the pockets and the chamber; a suitably-supported pressure-exerting ring arranged externally and extending circumferentially of the chamber below the pockets; upright calorically-expansible rods arranged within the pockets and in position to depress the ring, and means for preventing upward expansion of the rods.

90

45. In a roll-casting mold, an upper mold part or cope provided centrally with a chamber for receiving molten metal, with the surrounding wall or walls of the chamber formed by loam or molding-sand and provided with pockets arranged externally and spaced circumferentially of the chamber a suitable distance above the lower end of the cope, said wall or walls having holes connecting the pockets with the chamber; cutters or cut-offs arranged to sever the connections between

100

110

115

125

130

the pockets and the chamber; a suitably-supported pressure-exerting ring arranged externally and extending circumferentially of the chamber below the pockets; upright calorically-expansible rods arranged within the pockets and in position to depress the ring, and means for preventing upward expansion of the rods.

46. In a roll-casting mold, an upper mold part or cope provided centrally with a chamber for receiving molten metal, with the surrounding wall or walls of the chamber formed by loam or molding-sand and provided with pockets arranged externally and spaced circumferentially of the chamber a suitable distance above the lower end of the cope, said wall or walls having holes connecting the pockets with the chamber; a suitably-supported pressure-exerting ring arranged externally and extending circumferentially of the chamber below the pockets; upright calorically-expansible rods arranged within the pockets and in position to depress the ring; means for preventing upward expansion of the rods, and a body of sand contained within the lower portions of the pockets and surrounding the lower ends of the rods.

47. In a roll-casting mold, an upper mold part or cope provided centrally with a chamber for receiving molten metal, with the surrounding wall or walls of the chamber formed by loam or molding-sand and provided with pockets arranged externally and spaced circumferentially of the chamber a suitable distance above the lower end of the cope, said wall or walls provided at different elevations with holes connecting the pockets with the chamber; a suitably-supported pressure-exerting ring arranged externally and extending circumferentially of the chamber below the pockets; upright calorically-expansible rods arranged within the pockets and in position to depress the ring, and means for preventing upward expansion of the rods.

48. In a roll-casting mold, an upper mold part or cope provided centrally with a chamber for receiving molten metal, with the surrounding wall or walls of the chamber formed by loam or molding-sand and provided with pockets arranged externally and spaced circumferentially of the chamber a suitable distance above the lower end of the cope, said wall or walls provided at different elevations with holes connecting the pockets with the chamber; a suitably-supported pressure-exerting member arranged externally and extending circumferentially of the chamber below the pockets; upright calorically-expansible rods arranged within the pockets and in position to depress the ring, and means for tightening the rods downwardly against the aforesaid pressure-exerting member.

49. In a roll-casting mold, the combination, with the upper mold part or cope having a centrally-located chamber for receiving

molten metal, with the surrounding wall or walls of the chamber formed of loam or molding-sand, of a depressible pressure-exerting ring extending circumferentially of the lower end of the chamber and embedded in the aforesaid wall or walls, which ring is provided at its lower end with a beveled edge which has downwardly-projecting lugs.

50. In a roll-casting mold, the combination, with the upper mold part or cope having a centrally-located chamber for receiving molten metal, with the surrounding wall or walls of the chamber formed of loam or molding-sand, of a depressible pressure-exerting ring extending circumferentially of the lower end of the chamber and embedded in the aforesaid wall or walls, which ring is beveled at its lower end.

51. In a roll-casting mold, an upper mold part or cope provided centrally with a chamber for receiving molten metal, with the surrounding wall or walls of the said chamber formed of loam or molding-sand and provided externally of the chamber with pockets spaced circumferentially of the chamber and arranged a suitable distance above the lower end of the cope, said wall or walls also having holes connecting the pockets with the chamber; a suitably-supported pressure-exerting ring arranged externally and extending circumferentially of the chamber below the pockets; upright calorically-expansible rods arranged within the pockets and in position to depress the ring, and an abutment-forming vertically-adjustable weight arranged above the cope and overhanging the upper ends of the rods.

52. In a roll-casting mold, an upper mold part or cope provided centrally with a chamber for receiving molten metal, with the surrounding wall or walls of the said chamber formed of loam or molding-sand and provided externally of the chamber with pockets spaced circumferentially of the chamber and arranged a suitable distance above the lower end of the cope, said wall or walls also having holes connecting the pockets with the chamber; a suitably-supported pressure-exerting ring arranged externally and extending circumferentially of the chamber below the pockets; upright calorically-expansible rods arranged within the pockets and in position to depress the ring; suitably-supported shields arranged opposite the aforesaid holes between the latter and the rods, and means for preventing or limiting upward expansion of the rods.

53. In a roll-casting mold, the combination, with the upper mold part or cope having a centrally-located chamber for receiving molten metal and provided externally of the chamber with pockets spaced circumferentially of the chamber and arranged a suitable distance above the lower end of the cope, of a suitably-supported pressure-exerting ring ar-

ranged externally and extending circumferentially of the chamber below the pockets; upright calorically-expansible rods arranged within the pockets and in position to depress 5 the ring, and a suitably-supported abutment arranged above the cope and overhanging the upper ends of the rods.

54. In a roll-casting mold, the combination, with the upper mold part or cope having a centrally-located chamber for receiving molten metal and provided externally of the chamber with pockets spaced circumferentially of the chamber and arranged a suitable distance above the lower end of the cope, of a 10 suitably-supported pressure-exerting ring arranged externally and extending circumferentially of the chamber below the pockets; upright calorically-expansible rods arranged within the pockets and in position to depress 15 the ring, and vertically-adjustable means for preventing or limiting upward expansion of the rods.

55. In a roll-casting mold, the combination, with the upper mold part or cope having a centrally-located chamber for receiving molten metal, with the surrounding wall or walls of the chamber formed of loam or molding-sand and provided externally of the chamber with pockets spaced circumferentially of the chamber and arranged a suitable 20 distance above the lower end of the cope, of a 25 depressible pressure-exerting ring extending circumferentially of the lower end of the chamber and embedded in the aforesaid wall or walls below the pockets and provided at its outer side with outwardly-projecting outwardly-tapering lugs embedded in the said wall or walls; upright calorically-expansible rods within the pockets and arranged to de- 30 press the ring, and an abutment preventing or limiting upward expansion of the rods.

56. In a roll-casting mold, the combination, with the upper mold part or cope provided centrally with a chamber for receiving molten metal, with the surrounding wall or walls of the said chamber formed of loam or molding-sand and provided exteriorly of the chamber with pockets spaced circumferentially of the chamber and arranged a suitable 45 distance above the lower end of the cope, of a 50 suitably-supported depressible pressure-exerting ring arranged externally and extending circumferentially of the chamber below the pockets; upright calorically-expansible rods arranged to depress the ring; upright plates or partitions arranged radially of the pockets at the outer sides of the rods, and means for preventing or limiting upward ex- 55 pansion of the rods.

60. 57. In a roll-casting mold, the combination, with the upper mold part or cope provided centrally with a chamber for receiving molten metal, with the surrounding wall or walls of the chamber formed by loam or molding-sand and provided externally of the

chamber with pockets spaced circumferentially of the said wall or walls and arranged a suitable distance above the lower end of the cope, said wall or walls also having vertically-spaced holes connecting the pockets with the chamber, of a suitably-supported pressure-exerting ring arranged externally and extending circumferentially of the chamber below the pockets; calorically-expansible rods ex- 70 ranged within the pockets and in position to depress the ring; an abutment overhanging the upper ends of the rods, and wedges between the abutment and the said ends of the rods.

58. In a roll-casting mold, the combination, with the upper mold part or cope provided centrally with a chamber for receiving molten metal, with the surrounding wall or walls of the chamber formed of a body of loam or molding-sand, which body is surrounded by a metal casing provided at its upper end and externally with a laterally and outwardly projecting flange extending circumferentially of the casing, and a suitably-supported depressible pressure-exerting ring 85 arranged externally and extending circumferentially of the lower end of the aforesaid chamber; of upright rods arranged over and in position to depress the ring; an abutment-forming weight arranged above the cope and extending over the upper ends of the rods; bolts and nuts instrumental in attaching the weight to the said flange, with the bolts extending loosely through the weight, and spiral springs confined on the bolts and arranged to cushion the weight from above.

59. In a roll-casting mold, the combination, with the upper mold part or cope provided centrally with a chamber for receiving molten metal, with the surrounding wall or walls of the chamber formed of a body of loam or molding-sand, which body is surrounded by a metal casing, and a suitably-supported depressible pressure-exerting ring arranged externally and extending circumferentially of the lower portion of the aforesaid chamber, of upright rods arranged over and in position to depress the ring; and a vertically-adjustable abutment-forming weight arranged above the cope and extending over the upper ends of the rods.

60. In a roll-casting mold, the combination, with the upper mold part or cope provided centrally with a chamber for receiving molten metal, with the surrounding wall or walls of the chamber formed of a body of loam or molding-sand, which body is surrounded by a metal casing, and a suitably-supported and depressible pressure-exerting ring surrounding the lower end of the aforesaid chamber, of upright rods arranged over and in position to depress the ring; an abutment-forming weight arranged above the cope and extending over the upper ends of the rods and having vertically-arranged

- screw-threaded holes spaced circumferentially of the cope over the casing, which weight is provided in its upper side with recesses arranged over the aforesaid casing, 5 with the bottoms of the said recesses provided with bolt-holes; bolts and nuts instrumental in attaching the weight to the casing, with the bolts extending loosely through the said bolt-holes; spiral springs confined on the 10 bolts and arranged within the said recesses and adapted to cushion the weight from above, and correspondingly-threaded screws extending into engagement with the casing through the aforesaid screw-threaded holes.
- 15 61. In a roll-casting mold, the combination, with the upper mold part or cope provided centrally with a chamber for receiving molten metal, with the surrounding wall or walls of the chamber formed of a body of 15 loam or molding-sand, which body is surrounded by a metal casing, and a suitably-supported and compressible pressure-exerting ring surrounding the lower end of the aforesaid chamber, of upright rods arranged over 20 and in position to depress the ring; an abutment-forming weight arranged above the cope and extending over the upper ends of the rods and having vertically-arranged screw-threaded holes spaced circumferentially 25 of the cope over the casing; bolts and nuts instrumental in attaching the weight to the said flange, with the bolts extending loosely through the weight; spiral springs confined on the bolts and adapted to cushion 30 the weight from above, and correspondingly-threaded screws extending into engagement with the casing through the aforesaid screw-threaded holes.
62. In a roll-casting mold, the combination, with the upper mold part or cope provided centrally with a chamber for receiving molten metal, of a suitably-supported compressible pressure-exerting ring arranged externally and extending circumferentially of 40 the lower portion of the chamber, and calorically-operated means for depressing the said ring.
63. In a roll-casting mold, the combination, with the upper mold part or cope provided with a chamber for receiving molten metal, of a suitably-supported pressure-exerting member arranged externally and extending circumferentially of the lower portion of the chamber, said pressure-exerting 45 member being compressible independently of the walls of the said chamber, and means for depressing the said pressure-exerting member.
64. In a roll-casting mold, a lower mold 50 part or drag; a chill arranged over the drag and provided interiorly with a chamber extending from the upper end to the lower end of the chill; an upper mold part or cope arranged over the chill, with the aforesaid chill-chamber provided with vertically-spaced lateral enlargements extending circumferentially of the chill, with the bottom walls of the said chamber enlargements sloping downwardly and inwardly, with the cope provided centrally with a chamber which is 65 in communication with the chill-chamber, and with the drag provided centrally with a cavity having an inlet for molten metal and in communication with the chill-chamber; means whereby pressure can be exerted 70 downwardly upon the upper end of the contracting crust or shell of a casting formed in the chill, and a bearing for the lower end of the said shell or crust, which bearing is capable of being lowered.
65. In a roll-casting mold, a chill provided interiorly with a chamber which extends from the lower end of the chill upwardly and has vertically-spaced lateral enlargements extending circumferentially of the chill, with 75 the bottom walls of the chamber enlargements sloping downwardly and inwardly, and calorically-operated means whereby the contracting crust or shell of a casting formed in the chill is held in contact with the aforesaid walls until the casting has contracted 80 enough to become freed from the said walls.
66. In a roll-casting mold, the combination, with an upright chill provided interiorly with a chamber extending from the upper to the lower end of the chill, of calorically-operated means arranged at the upper end of the chill and in position to depress a casting formed in the chill.
67. In a roll-casting mold, the combination, with an upright chill provided interiorly with a chamber extending from the upper to the lower end of the chill, of yieldingly-operating means for exerting pressure 90 downwardly upon the upper end of a casting 95 formed in the chill.
68. In a roll-casting mold, the combination, with an upright chill provided interiorly with a chamber extending from the upper to the lower end of the chill, of calorically-operated means arranged and adapted to depress a casting formed in the chill, and compressible means arranged under and in position to support the said casting.
- In testimony whereof I sign the foregoing 100 specification in the presence of two witnesses.
- RALPH H. WEST.
